TIRE

Arthur C. Blankenship, Detroit, Robert F. Bogan, Grosse Pointe Farms, and William L. Shesterkin, Roseville, Mich., assignors to United States Rubber Company, New York, N.Y., a corporation of New Jersey

Filed May 13, 1965, Ser. No. 85,260

Term of patent 14 years

(Cl. D90—20)

Fig. 1

FIG. 1 is a perspective view of a tire embodying our new design, it being understood that the full line portion is repeated throughout the circumference of the tire, shown by means of broken lines;

FIG. 2 is an enlarged transverse sectional view of the tire shown in FIG. 1;

FIG. 3 is a fragmentary elevational view of the tire taken from the viewing position indicated by line III-III in FIG. 2; and

FIG. 4 is an enlarged fragmentary perspective view, partially in section, of the full-line portion of the tire shown in FIGS. 2 and 3.

The dominant features of our design reside in those portions shown in full lines in the drawings.

We claim:

The ornamental design for a tire, substantially as shown and described.
